UNITED STATES PATENT OFFICE

92,266

DESIGN FOR A METAL GOLF CLUB HEAD

George Nicoll and Robert Nicoll, Leven, Scotland

Application March 17, 1934, Serial No. 51,088

Term of patent 7 years

To all whom it may concern:

Be it known that we, GEORGE NICOLL and ROBERT NICOLL, subjects of the King of the United Kingdom of Great Britain, and residents of Leven, Fife, Scotland, have invented a new, original, and ornamental Design for a Metal Golf Club Head, of which the following is a specification, reference being had to the accompanying drawing, forming part thereof.

Fig. 1 is a view looking on the back and Fig. 2 an edge view of the club head. Figs. 3 and 4 are views looking on the club head in the direction of the arrows A and B respectively in Fig. 2. We claim:

The ornamental design for a metal golf club head as shown.

GEORGE NICOLL.
ROBERT NICOLL.
